UNITED STATES PATENT OFFICE.

WILLIAM C. SLEEMAN, OF BIRMINGHAM, ALABAMA.

RAILWAY-CAR TRUCK.

Application filed February 1, 1927. Serial No. 165,122.

This invention relates to car trucks and aims to provide an improved spring supporting arrangement whereby car trucks of different load carrying capacities can be built with side frames, bolsters and spring planks of uniform size.

The invention will be apparent from the following specification when read in connection with the accompanying drawings in which—

Fig. 1 is a side elevation of a portion of a car truck embodying my invention;

Fig. 2 is a top plan thereof;

Fig. 3 is a transverse section of a portion 15 of the truck the section being on the line 3—3 of Fig. 2.

Fig. 4 is a plan of a unit group of bolster supporting springs;

Figs. 5, 6 and 7 are plan views showing 20 the manner of varying the grouping of the springs in accordance with the load carrying capacity of different trucks for which the construction is adapted to be used.

Referring in detail to the drawings, 25 25 represents one truck side frame as a whole which is composed of the compression member 12, tension member 14, upright columns 16. The latter are provided with guiding surfaces 18 for coaction with guide ribs 20 formed on the truck bolster 22.

The spacing between the column supports 16 is greater than in the usual form of car truck and the design is such that a unit group of springs can be readily accommodated between these supports. As thus arranged car trucks of different capacities can be supplied by using side frames and other parts, if desired, of uniform size. This effects manufacturing economies and also 40 enables the railroads to standardize their rolling stock with resulting saving in maintenance costs.

Extending transversely of the truck below the bolster is a spring plank 24 having upturned flanges 26 which serve to approximately position the unit group of springs to be presently described. The unit group of springs, for example, that shown in Figs. 3 and 4, consists of upper and lower retaining plates 28 and 30 connected by an axial bolt 32. The head 34 of this bolt is seated in a depression 36 formed in plate 28 and the shank of the bolt passes through a suitable opening formed in the plate. At the lower end the bolt carries a nut 38 which is seated in a depression 40 formed in the lower plate

30 and the shank passes freely through an opening formed in the plate so that as the bolster moves up and down the bolt can ride through the opening in the lower plate, the 60 nut at this time entering a clearance opening 42 formed in the upper side of the tension member 14 of the side frame. As best shown in Figs. 4 to 7 inclusive, the unit group of springs is so arranged that the 65 carrying capacity of the truck may be readily varied merely by using a different number of springs. For example, in Fig. 5 it is noted that the unit group is made up of six springs 44. In Fig. 6 there are outer 70 springs indicated at 44, and a central spring 46 which is of the same size and capacity as the springs 44 and located within which is a smaller spring 48. This arrangement 75 will give a greater carrying capacity than the arrangement of Fig. 5 yet it will be readily seen that the unit group of springs is housed within the same amount of space and in fact is mounted between a spring plank 80 and truck bolster of the same size utilized in connection with the spring grouping shown in Fig. 5. To secure a much greater carrying capacity, the unit group of springs such as shown in Fig. 7 is preferably used 85 which consists of seven of the larger size springs 44 and also seven of the smaller diameter springs 48 nested within the larger springs. It will be understood that a truck of intermediate capacity can be secured by adding to the arrangement of Fig. 6 one 90 or more of the smaller diameter springs.

The spring retaining plates 28 and 30 are preferably of non-circular form. In the embodiment illustrated they are of substantially hexagonal shape. This form of retaining plate is advantageous because it compels the workman to properly position the unit group of springs with respect to the other parts of the truck in such a way that the most effective distribution of the 100 load is secured. Reference to Fig. 2 will show that the center of the group of springs is a point which lies at the intersection of the line *a*—*b* which is on the center line of the tension member 14 of the side frame as viewed in plan, and a line *c*—*d* drawn through the longitudinal axis of the spring plank. The apothem or flat sides of the hexagon lie substantially parallel to the upturned flanges 26 of the spring plank and the distance between the opposed points of the hexagon is greater than the distance be- 105 110

tween the upturned flanges, hence, the unit group of springs must be inserted in the position shown. This is important because it properly distributes the weight or load in a predetermined manner. It is noted that at the ends there will always be two transversely aligned springs symmetrically arranged on opposite sides of the center line $a-b$ of the tension member and the arrangement is such that there are at least two springs which lie along the center line $c-d$ of the spring plank. When a greater capacity is required and an additional spring of large size is required, it is added in the center. This equally distributes the panel load of the bolster as will be apparent from examination of Figs. 6 and 7.

The spring retaining plates 28 and 30, respectively, are provided with outwardly extending projections 29 and 31 which are adapted to enter openings 33 and 35 formed respectively in the bolster and the spring plank so as to correctly position or center the unit group of springs with these parts of the truck.

The spring plates are also formed with inner projections which center the springs with respect to the plates as shown in Figs. 1 and 2.

My improved construction is an improvement over trucks heretofore proposed such as the Dalman and Chiles trucks which require certain stepped portions in side frames in order to accommodate additional springs necessary for carrying required loads. With

my design it is apparent that the same size side frame, spring plank and bolster can be used for trucks of different capacities, and that varying load conditions are taken care of by inserting a unit group of springs to suit requirements.

Various modifications and substitution of equivalents may be made without departing from the invention as defined in the appended claims.

What I claim is:

1. A railway car truck including a side frame, a truck bolster, a spring plank, a group of more than four springs symmetrically arranged about a common point with at least two of said springs in alignment with the longitudinal center line of said spring plank, said spring plank having upturned flanges and a pair of spring retaining plates of non-circular form adapted to interfit with said flanges to compel the correct alignment of said springs when assembling.

2. A car truck including a side frame, a bolster, a spring plank with upturned flanges, a group of at least six springs symmetrically arranged about a common center, a pair of connected hexagonal retainer plates carrying spring centering projections adapted to position said group of springs between said flanges so that at least two springs are aligned with the longitudinal center of said spring plank.

In witness whereof, I have hereunto signed my name.

WILLIAM C. SLEEMAN.
